US00D705821S

(12) **United States Design Patent**
Frazier

(10) **Patent No.:** **US D705,821 S**
(45) **Date of Patent:** **** May 27, 2014**

(54) **CONFIGURABLE INSERT FOR A
DOWNHOLE PLUG**

(71) Applicant: **W. Lynn Frazier**, Corpus Christi, TX
(US)

(72) Inventor: **W. Lynn Frazier**, Corpus Christi, TX
(US)

(**) Term: **14 Years**

(21) Appl. No.: **29/445,834**

(22) Filed: **Feb. 18, 2013**

Related U.S. Application Data

(63) Continuation of application No. 29/398,384, filed on Jul. 29, 2011, now Pat. No. Des. 694,280.
